UNITED STATES PATENT OFFICE.

IGNATZ HARTMANN, OF ST. LOUIS, MISSOURI.

BUCKLE.

SPECIFICATION forming part of Letters Patent No. 291,726, dated January 8, 1884.

Application filed October 22, 1883. (No model.)

To all whom it may concern:

Be it known that I, IGNATZ HARTMANN, of the city of St. Louis, State of Missouri, have made a new and useful Improvement in 5 Buckles, of which the following is a full, clear, and exact description, reference being had to the annexed drawings, making part of this specification, in which—

Figure 1 is a view in perspective, showing 10 the band which is attached to the buckle; Fig. 2, a view in perspective, showing a buckle and strap having the improvement, the strap being unbuckled; Fig. 3, a view in perspective, showing the strap buckled.

15 The same letters of reference denote the same parts.

The present invention relates especially to the band which is attached to the tongue-bar of the buckle.

20 A represents a buckle, and B a strap, of the ordinary kind and connected in the ordinary manner.

C represents a band of the rectangular shape. (Shown more distinctly in Fig. 1.) The sides c 25 c of this band C are perforated at c' c', to receive the tongue-bar a, which passes through

the sides of the band and connects it with the buckle in the manner shown in Figs. 2 and 3. It will be noticed that the perforations c' c' are midway between the top c² and the bottom c³ 30 of the band. This leaves a space beneath the tongue-bar through which the part b of the strap can pass, and a space above the tongue-bar through which the end b' of the strap can be passed, as shown in Fig. 3. 35

I am aware that buckles have been provided with double loop, and therefore do not broadly claim such a loop; but

I claim—

A double loop hinged at its center to the 40 tongue-bar of a buckle, and extending from the tongue-bar directly upward and downward, for the purpose of binding the strap directly opposite and against the tongue-bar, as described. 45

In testimony whereof I have affixed my signature, in presence of two witnesses, this 17th day of October, 1883.

IGNATZ HARTMANN.

Witnesses:

PAUL BAKEWELL,
J. W. RIDDLE.
